DOOR OPERATING SYSTEM

John R. Newkirk, Rahway, N. J., assignor to National Pneumatic Company, New York, N. Y., a corporation of West Virginia

Application October 17, 1939, Serial No. 299,817

5 Claims. (Cl. 268—64)

This invention is concerned with door operating mechanism and envisions the particular object of providing an equalized mechanism by means of which a single engine may operate two door shafts in spaced synchronism so that door leaves connected thereto will move in exact unison.

Other and more detailed objects of the invention will become apparent from the following description when taken in connection with the attached drawings.

This invention resides substantially in the combination, construction, arrangement and relative location of parts, all as will be set forth in detail in the following description.

In the accompanying drawings.

Figure 1 is a top plan view of one form of mechanism in accordance with this invention, with the parts broken away to facilitate illustration of the structure on a sufficiently large scale;

Figure 2 is a longitudinal, central, cross-sectional view through the engine of Fig. 1.

It is common practice on vehicles such as street cars, and in other places, to provide a closure for a door opening consisting of a pair of sections, both of which are moved to open and close the doorway. These two sections may be individually operated in the case of power operated doors by separate motive devices, or as has been proposed from time to time, they may both be moved by a single motive device connected thereto with suitable linkages.

In the past difficulty has been encountered in providing linkage systems and interconnecting the door shafts on which the door sections are mounted by means of them to the engine, so as to secure the desired practical object of having both door sections move in synchronism. Frequently, even with arrangements which cause the doors to move more or less in synchronism, it has been found that with such arrangements when one door section has been fully opened and the door has come to rest, the other section is not fully opened. Furthermore, the lack of equalization in movement of the door sections has resulted in setting up undue stresses and strains in the mechanism.

In a general sense it may be said to be the main object of this invention to provide a simple arrangement whereby a single engine is so mounted and interconnected that a pair of door shafts with the door sections connected thereto move in unison and furthermore that their movements are so equalized that there is a balance of stresses and strains set up in the mechanism,

comprising the normal forces required to operate it.

Referring to Figures 1 and 2, in which one form of the invention is illustrated, there is shown in plan at 1 a plate or other suitable form of base or support adapted to be mounted directly over a door opening. At 4 and 4' are a pair of door shafts which as commonly employed extend vertically in parallel relationship and which are positioned at the two sides of the door opening. 5 These shafts are usually journaled in a pair of vertically spaced bearings, one of which is provided for each shaft near its lower end, and the other of which is provided for each shaft at its upper end.

In Figure 1 the upper bearings for the shafts 4 and 4' have been illustrated at 2 and 3 mounted on or secured to the supporting plate 1 in any suitable manner. Secured to the upper ends of the shafts 4 and 4', above the respective bearings, 10 are the levers 5 and 6 respectively, which are respectively pivotally connected at 7 and 8 to the links or rods 9 and 10.

The engine is shown as comprising a cylinder 12 provided at one end with a head terminating in an internal threaded lug 11 in which the link 10 is secured. The other end of the cylinder is closed by a detachable head 13, through which the rod 9 passes, which comprises the piston rod for the engine.

As shown in Figure 2, the piston rod 9 is secured to a piston 14 which is mounted for reciprocation within the cylinder 12. The piston rod or connecting link 9 passes through a packing gland 17 which is in the form of a ring of suitable flexible material such as rubber, which ring is held in a recess by means of a disc or plate 18 threaded into a suitable recess in the head 13. The plate or disc 18 is provided with a series of ports 19 the function of which is to be explained later.

As is clearly shown in Fig. 2, the ring or collar 17 is provided with a peripheral groove of such dimensions as to reduce the axial thickness of the rim of the collar on each side of the groove 45 sufficiently to make those rims flexible. Their function will be described later.

The piston 14 is provided with three peripheral grooves, the central one of which is of less depth than the other two and in which is mounted a 50 ring 23 of suitable flexible material such as rubber to form a piston ring. In the other two peripheral grooves are mounted similar rings also connecting as piston rings, but in this case having grooves on their internal faces to form the flexible 55

internal rims similar to those described in connection with the collar 17. The internal diameter of the flexible rings 20 is less than the diameter of the peripheral grooves at their base in 5 which they lie. This provides annular spaces which are connected to the respective ends of the cylinder 12 by the passages 21 and 22. The functions of this arrangement will be described later.

The right hand end of cylinder 12 is provided 10 with a boss which is in communication with that end of that cylinder and is adapted to receive a pressure fluid pipe connection. In a similar way the boss 15 is formed on the head 13 for supplying pressure fluid through a suitable connection 15 to the left hand end of cylinder 12.

Secured to the lower side of cylinder 12 is a depending pin 24 which engages the bifurcated end 25 of a lever 26. Lever 26 is pivotally mounted intermediate its ends on a pivot pin 20 27 mounted on a plate 28 secured to the base 1. The opposite end of lever 26 is pivotally connected at 29 to a link 30 which, in turn, is pivotally connected at 31 to the lever 5 at a point intermediate the ends thereof.

25 In describing the operation of this arrangement, it is to be noted that the respective ends of the cylinder 12 may be alternately connected by any suitable form of valve to a pressure fluid source and to the atmosphere. It will be assumed that the parts are shown in door closed position. In order to open the doors the left hand end of cylinder 12 is connected to the pressure fluid source while the right hand end is left open to exhaust. The result is that pressure 30 fluid is fed into the left hand end of cylinder 12 thereby causing piston 14 to move to the right and by reason of the reaction forces the cylinder 12 is caused to move to the left.

As a result of this movement it will be seen 40 that lever 5 and shaft 4 rotate in a clockwise direction (Fig. 1) and lever 6 and shaft 4' move in a counter-clockwise direction. As the cylinder 12 moves to the left lever 26 moves in a counter-clockwise direction about the pivot pin 27. It 45 will be noted that the end 25 of this lever is slotted so that the pin 24 can move longitudinally thereof leaving the cylinder free to move as required by the linkage system. The movement of the lever 26 is constrained so as to be 50 proportionate to the movement of lever 5 by reason of the linkage connection 30. With this arrangement it will be seen that the engine is more or less freely floating and since it in effect comprises a sort of variable link the parts are 55 permitted to assume a balanced equally stressed condition whereby the door shafts move in unison and both are assured of just the right amount of movement to insure full opening and full closing of each door section.

60 With reference to Figure 2, it will be seen that when the pressure fluid is supplied to the left hand end of cylinder 12 it acts through the passages 19 on the flexible peripheries of the collar 17 as well as on the collar itself to aid in forming a fluid tight sliding engagement with the piston rod 9. It likewise acts through the passages 22 on the flexible inner rims of the left hand ring 20 as well as on the ring itself to aid in forming a tight fitting piston ring. The right 65 hand end of cylinder 12 is open to exhaust through the boss 16. In order to close the door the connection to boss 15 is opened to exhaust and the connection to boss 16 is open to the pressure fluid source so that the piston moves back 70 to the position shown in Fig. 2 causing a reverse 75

operation of the door shafts. During the reverse operation the pressure fluid acts through the passages 22 to cause the ring 20 to form a tight fit with the cylinder.

From the above description it will be apparent to those skilled in the art that this invention resides in certain principles of construction and operation which may be embodied in other physical forms without departure from the novel scope thereof. 5

I do not, therefore, desire to be limited by the particular forms of invention submitted for illustrative purposes, but rather by the true scope of the claims granted me. 10

What is claimed is:

1. A door operating system as described, comprising a pair of shafts journaled for rotation, an engine comprising a cylinder and a piston, means for connecting the cylinder to one of said door shafts, and the piston to the other, a fixed 20 pivotal support, means for pivotally connecting the cylinder to said support, and a pivoted linkage connection between said support and one of said shafts.

2. In a mechanism for operating a pair of 25 shafts in synchronism, the combination including a pair of shafts journaled for rotation, an engine comprising a cylinder and a piston, arms secured to said shafts respectively, means for connecting one of said arms to said cylinder, 30 means for connecting the other of said arms to said piston, a pivot support mounted adjacent said engine, a lever pivotally mounted thereon intermediate its ends, means on said cylinder for pivotally engaging one end of said lever, and a 35 link pivotally interconnecting the other end of said lever with one of said arms.

3. In a mechanism for operating a pair of shafts in synchronism, the combination including a pair of shafts journaled for rotation, an 40 engine comprising a cylinder and a piston, arms secured to said shafts respectively, means for connecting one of said arms to said cylinder, means for connecting the other of said arms to said piston, a pivot support mounted adjacent 45 said engine, a lever pivotally mounted thereon intermediate its ends, means on said cylinder for pivotally engaging one end of said lever, and a link pivotally interconnecting the other end of said lever with said arm connected to said pis- 50 ton.

4. In an arrangement as disclosed, a pair of shafts journaled for rotation, an engine for operating said shafts comprising a cylinder and a piston, means for pivotally connecting the cylinder to one of said shafts, means for pivotally connecting the piston to the other of said shafts, said connecting means forming the support for said engine, means for pivotally connecting said cylinder to a fixed support, and a link pivotally 60 connecting the means connected to the piston to the same fixed pivotal support. 55

5. A door operating mechanism including a pair of door shafts mounted for rotation, an engine for operating said shafts comprising a 65 cylinder and a piston, means for pivotally connecting the cylinder at one end to one of said shafts and the piston to the other of said shafts, a fixed pivot support, means for pivotally connecting the cylinder intermediate its ends to 70 said pivotal support, and pivoted links interconnecting one of said shafts with said pivotal support. 70
